HEATING BOILER

Application filed May 13, 1929, Serial No. 362,805, and in the Netherlands August 8, 1928.

The object of this invention is a heating boiler which is economical in operation and in which the coal moves by gravity from a feed hopper into the furnace.

Boilers of this type often have the disadvantage that a considerable amount of carbon monoxide escapes thru the stack and that explosions are likely to occur in the feed hopper. Moreover, it takes a considerable time before the fire can be animated.

In accordance with my present invention, which has for its object to avoid the aforesaid disadvantages, the boiler is provided with a furnace having the following characteristic features. Provided on the one side (the front side) is the feed hopper and below the same, extending in a rearward direction with respect thereto, is a downwardly sloping guiding surface for the coal, the slope of the said surface corresponding to the natural talus of the fuel. Below said guiding surface may be provided an inlet opening for combustion air and on a still lower level is a cleaning and air inlet opening provided with a suitable door. Arranged on the other side (the rear side) of the furnace are three superposed openings, the upper one being for the inlet of air substantially on a level with the lower end of the slope of the incandescent coal, the central one for the inlet of air into the central part of the fire zone, whereas the lower opening is for the removal of ashes and clinker and also for the inlet of air required for the formation of carbon monoxide.

Preferably the upper air inlet opening on the rear side opens below a baffle, so that the air fed thru said opening is thoroughly preheated, the preheating being favorably affected by the air admitted thru the central opening heating the coal in the central part of the fire to a high temperature.

Preferably, the feed hopper has a discharge opening in the form of a slot, the height of which does not exceed 10 cm. but which in practice should by preference not be higher than say 6-7 cm. Anyone skilled in the art will recognize that this height is considerably smaller than that in known furnaces provided with a feed hopper.

The above arrangement of the air inlet

openings relative to one another enables the combustion to be controlled in a perfect manner.

In order that my invention may be well understood I shall now proceed to describe the operation of a preferred embodiment shown in vertical sectional elevation on the annexed drawing.

The boiler preferably is composed of a plurality of sections partly filled with water and suitably spaced so that the hot combustion gases can freely pass between them and whereupon collect in a transverse flue leading to the chimney.

The feed hopper 1 on the front side of the boiler has a slot shaped discharge opening 2 below which the downwardly sloping supporting and guiding surface 3 for the coal extends thru a suitable distance. Just below the lower end of said guiding surface is an air inlet passage 4 provided with a door or a slide valve which is only opened when it is desired for the fire to be quickly animated. On a still lower level is a wide duct 5 provided with a cleaning door, said door having means for admitting an adjustable amount of combustion air into the combustion space.

On the rear side of the boiler is the flue 6 leading to the stack. The slope or talus 7 of the fuel extends from the discharge slot 2 downward to the bottom edge of an air inlet passage 8 adapted to introduce air for the combustion of any carbon monoxide that may reach the upper zone of the fire. Said passage 8 is the equivalent of known inlets for secondary combustion air into furnaces.

A relatively wide duct 10 near the bottom serves for the inlet of a controlled amount of air and also for the removal of clinker and ashes from the non-apertured fire plate 14 which supports the fire clinkers and ashes. Said amount of air principally serves for forming carbon monoxide.

Intermediate between the passages 8 and 10 is a third inlet 9 opening into the central portion of the fire zone. Air entering thru said passage causes a high temperature of the coal in said zone, so that the air entering thru passage 8 is preheated and thereby specially adapted to combine with and completely burn

the carbon monoxide formed in the lower zone. This preheating is favorably affected by the presence of a baffle 11, which compels the air to flow over and in close contact with the incandescent coal.

5 The coal between the fire zone and the slot 2 remains relatively cool and the gases developed therefrom are burnt in the usual manner by the secondary air entering thru the passage 8. This combustion is promoted 10 by the high temperature of the central zone due to the admission of air thru the passage 9.

15 As the coal sliding downward over the sloping guiding surface 3 begins to glow immediately beyond the lower end of said surface and thereby to develop a large amount of combustible gases, the passage 4 is exceptionally adapted for the inlet of air when it is desired for the fire to be animated.

20 It will be noted that the passage 4 opens into a zone where the coal is in incandescent state. As the layer of coal here is relatively thin, especially when the feed hopper has a narrow discharge slot, the fire is prevented 25 from spreading into the feed hopper.

What I claim is:—

1. In combination with a heating boiler, a non-apertured fire plate, a feed hopper provided on the front side and having a discharge opening and also having a downwardly sloping guiding surface for the coal which by gravity moves from the hopper into the furnace, a cleaning and air inlet opening provided on the front side, a combustion air inlet provided on the rear side on a level below the discharge opening of the feed hopper but above the rear end of the talus of the fuel in the furnace, and an air inlet and cleaning opening provided on the rear side a suitable distance below the said combustion air inlet opening.

2. In combination with a heating boiler, a non-apertured fire plate, a feed hopper provided on the front side and having a discharge opening and also a downwardly sloping guiding surface for the coal which by gravity moves from the hopper into the furnace, a cleaning and air inlet opening provided on the front side, a combustion air inlet provided on the rear side on a level below the discharge opening of the feed hopper but above the rear end of the talus of the fuel in the furnace, an air inlet and cleaning opening provided on the rear side a suitable distance below the said combustion air inlet opening, and a second combustion air inlet opening on the front side intermediate between the said downwardly sloping guiding surface and the said cleaning and air inlet opening.

3. In combination with a heating boiler, a non-apertured fire plate, a feed hopper provided on the front side and having a discharge opening and also a downwardly sloping guiding surface for the coal which by

gravity moves from the hopper into the furnace, a cleaning and air inlet opening provided on the front side, a combustion air inlet provided on the rear side on a level below the discharge opening of the feed hopper but above the rear end of the talus of the fuel in the furnace, an air inlet and cleaning opening provided on the rear side a suitable distance below the said combustion air inlet opening, an additional air inlet upon the rear side adapted to introduce air to the central portion of the fire zone, and a second combustion air inlet opening on the front side intermediate between the said downwardly sloping guiding surface and the said cleaning and air inlet opening.

In testimony whereof I affix my signature.

LEON RAINCHON.
